UNITED STATES PATENT OFFICE

WILLIAM I. MC LAUGHLIN, OF SAN FRANCISCO, CALIFORNIA, ASSIGNOR TO STANDARD OIL COMPANY OF CALIFORNIA, OF SAN FRANCISCO, CALIFORNIA, A CORPORATION OF DELAWARE

CORE DRILL AND BIT

Application filed July 28, 1926. Serial No. 125,873.

This invention relates generally to drills of the rotary type which are adapted to remove a core from the strata being drilled.

Rotary core drills commonly comprise a core retainer rotatably mounted within a core barrel, the barrel having a suitable bit at its lower end to cut away the formation about a central core which is permitted to progress upwardly into the retainer. Lubricating mud is generally circulated down through the drill stem and discharged adjacent the bit to carry away the cuttings and reduce friction. With the ordinary type of bit the core is frequently fractured or burned during the process of drilling or is washed away by the lubricating mud, thus making it of doubtful or useless value for determining the condition of the sub-strata. I have found that this fracturing and burning of the core is caused by excessive friction between the bit and the formation being drilled due to faulty lubrication, and to inadequate facilities for carrying away the borings, with the result that the teeth become clogged with mud. This fracturing also frequently results from friction due to relatively large surfaces in contact between the bit and the core, to the absence of positive means for centering the bit and to the entrance of borings into the core retainer.

It is an object of this invention to devise a core bit in which all tendency to fracture or to burn the core will be minimized.

It is a further object of this invention to devise a core bit which will be adequately lubricated to reduce friction and effectively remove all borings.

It is a further object of this invention to construct a core bit in such a manner as to prevent deposits of mud forming upon the teeth.

It is a further object of this invention to devise a core bit which will be self-centering to prevent side sway and resulting fracturing of the core.

It is a further object of this invention to prevent washing away of the core by the lubricating mud which is being circulated through the drill.

It is another object of this invention to de-

vise a core bit of relatively simple construction which may be attached to any standard core barrel and which will cut rapidly in soft formations.

It is another object of this invention to devise a core drill incorporating a particular type of bit which will prevent entry of cuttings into the core retainer.

Further objects of the invention will appear from the following description in which I have set forth the preferred embodiment of my invention. It is to be understood that the scope of the invention is to be determined from the appended claims and the state of the prior art.

Referring to the drawings:

Figure 1 is a side elevational view showing a bit constructed in accordance with this invention.

Fig. 2 is a bottom view showing the arrangement of the teeth upon the bit.

Fig. 3 is a cross section taken along the line 3—3 of Fig. 2 showing the bit attached to a suitable form of core barrel.

The invention comprises generally a particular form of bit which is adapted to be secured to a suitable form of core barrel, preferably of the type having an inner rotatable core retainer. Lubricating mud is circulated downwardly through the core barrel and discharged through passageways provided in the body of the bit, these passageways being arranged so as to discharge the mud directly from the lower face of the bit. The cutting teeth depend from the lower face of the bit and are spaced regularly about the axis of the barrel.

Thus as shown in the drawings (Fig. 3) the bit has been indicated generally at 10 and has been shown as secured to the lower end of a hollow core barrel 11, the barrel being secured at its upper end to a suitable pipe string or drill stem. Within the core barrel 11 there has been shown a core retainer 12 of suitable construction which is adapted to receive a core formed by the bit 10. The bit itself comprises a body member 13 which may be provided with a suitable threaded extension or sleeve 14 for attachment to the lower end of the core barrel 11. In order

to pass the core through the retainer 12 the body member is provided with a central bore 16 having a minimum diameter which is substantially less than the internal diameter of the core retainer.

In order to aid in carrying away borings from the bottom of the bit and in order to prevent their entry into the core retainer the lower face of the bit is preferably sloped 10 upwardly away from the central bore 16.

Thus the bottom face of the bit has been shown as provided with two beveled surfaces 17 and 18, the outer bevel 18 being at a more acute angle than the inner bevel.

15 Geometrically these beveled portions are substantially in the form of two intersecting conical surfaces having a common axis, the outer conical surface having a substantially greater slope ratio than the inner. Depending from the lower face of the bit are a plurality of teeth 19 which are regularly spaced about the central bore 16. The particular form of teeth shown are commonly known as the fish tail type, two diametrically opposite teeth forming the two fins for one tail. Thus the rear side of each tooth is shown as beveled as at 20 to form a cutting edge 21, this cutting edge being advanced in the direction of rotation beyond 30 the forward side of the tooth. In order to secure more efficient cutting action and to direct cuttings away from the central bore 16, these cutting edges are preferably inclined rearwardly from the direction of rotation with respect to the radius of the bit as indicated in Fig. 2. Thus the advancing face of each tooth is at an angle to the direction of rotation in order to exert a shearing action upon the formation being cut. As a 40 means for centering the bit and in order to prevent side sway the cutting edges are not extended to lie within a plane surface but are sloped downwardly away from the central bore so that the core will be formed with 45 a conical base.

The lubricating mud is preferably introduced directly along the lower face of the bit and thus there has been provided a plurality of passageways which communicate at 50 their upper ends with the space between the core retainer 12 and the barrel 11, and at their lower ends communicate directly with the lower face of the bit adjacent the intersection between the beveled surfaces 17 and 55 18. In some instances a single passageway between two successive teeth is sufficient although it is preferable to provide two passageways on either side of each tooth as shown in Fig. 2. With this arrangement the lubricating mud is directed against the sides of the teeth, thus washing away and preventing the accumulation of mud deposits. In order to minimize friction between the sides of the bit and the core barrel and the walls 60 65 of the formation being cut, the teeth are pref-

erably provided with extensions 26 which project upwardly above the beveled surface 18 and thus cause the bit to act as a reamer to establish the maximum diameter of the hole being drilled. This arrangement also serves to facilitate removal of the borings from the bit by the lubricating mud since more space is provided between the periphery of the barrel and the walls of the formation.

70 The particular form of core retainer employed should be constructed in such a manner as to direct lubricating mud downwardly between the retainer and the barrel through the passageways 23 and to prevent its entrance into the retainer between the retainer and the bit. The particular form of retainer shown is split longitudinally to provide two halves 27 to which are secured at their lower ends a ring 28. The central bore 16 is enlarged as at 29 snugly to receive the lower end of this retainer, thus forming a shoulder 25 adjacent the lower end of the bit. The ring 28 may be provided with centering dogs 30 and with a bearing 31 for reducing the friction between the retainer and bit. Spring fingers 32 may also be provided within the retainer for centering and marking the core. The central bore 16 and thus the shoulder 25 is preferably flared upwardly as shown in Fig. 3 in order to reduce the amount of surface which is in frictional contact with the core being formed.

75 80 85 90 95 100 105 110 115 120 125 130 When the device is in operation lubricating mud introduced into the pipe string is circulated downwardly between the core retainer and barrel and discharged from the lower face of the bit through the passageways 23. The mud as it is discharged washes against the sides of the teeth, thus carrying away borings as quickly as they are formed and preventing mud deposits. The combined effect of having the cutting edges inclined rearwardly from the radius of the bit in the direction of rotation, and the upwardly sloped lower face of the bit, serves to minimize entry of the cuttings into the core retainer and therefore the core is permitted to progress upwardly into the retainer without danger of clogging. Because of the proximity between the inner ends of the cutting edges and the lower end of the central bore 16, the circulating mud will not tend to wash against the face of the core to cause it to be worn away. The fact that the cutting edges are also inclined downwardly from the central bore, serves to form a strong conical base for the core, thus minimizing the tendency of the core to break at its base and also tends to center the bit upon the formation being cut, thus preventing side sway. The lubrication may be maintained adequate at all times to keep the bit relatively cool, thus reducing friction and preventing burning of the core. The extensions 26 serve to ream

out the hold and also to agitate the cuttings and thus assist in preventing clogging of the bit.

I claim:

- 5 1. A rotary core bit comprising a body member having a central bore, the lower face of the member having annular surfaces beveled upwardly away from the bore on two distinct angles to form a face corresponding generally to a pair of concentric intersecting cones forming a circular shoulder along their line of intersection.
- 10 2. A rotary core bit comprising a body member having a central bore, the lower end of said member having annular surfaces beveled on two distinct angles to form a face corresponding generally to a pair of concentric intersecting cones forming a circular shoulder along their line of intersection, the lower face sloped upwardly away from the bore, and a plurality of teeth disposed upon said face, said teeth extending along both bevels of said face and beyond the outer periphery of the body.
- 15 3. A rotary core bit comprising a body member having a central bore, the lower end of said body member having annular surfaces beveled on two distinct angles to form a face corresponding generally to a pair of concentric intersecting cones forming a circular shoulder along their line of intersection, the lower face sloped upwardly away from the bore, and a plurality of teeth disposed upon said face, said teeth extending along both bevels of said face and beyond the outer periphery of the body, said teeth also having edges sloped downwardly away from said bore.
- 20 4. A rotary core bit comprising a body member having a central bore to receive a core, a plurality of teeth depending from the lower face of said member, the lower face of said member being beveled upwardly away from the bore on at least two distinct angles and forming a face corresponding generally to a pair of concentric intersecting cones forming a circular shoulder along their line of intersection, and passages for fluid communicating with said beveled face.
- 25 5. A rotary core bit comprising a body member having a central bore to receive a core, a plurality of teeth depending from the lower face of said member, the lower face of said member being beveled upwardly away from the bore on at least two distinct angles and forming a face corresponding generally to a pair of concentric intersecting cones forming a circular shoulder along their line of intersection, and passages for fluid communicating with the lower portion of said beveled face between said teeth.

In testimony whereof, I have hereunto set my hand.

WILLIAM I. McLAUGHLIN.
